UNITED STATES PATENT OFFICE.

HERBERT HENDERSON, OF PORT ARTHUR, TEXAS, ASSIGNOR TO GULF REFINING COMPANY, OF PITTSBURGH, PENNSYLVANIA, A CORPORATION OF TEXAS.

STILL AND STILL-SETTING.

1,171,720.

Specification of Letters Patent. Patented Feb. 15, 1916.

Application filed July 9, 1915. Serial No. 38,987.

To all whom it may concern:

Be it known that I, HERBERT HENDERSON, a citizen of the United States, residing at Port Arthur, in the county of Jefferson and State of Texas, have invented certain new and useful Improvements in Stills and Still-Settings, of which the following is a specification.

This invention relates to stills and still settings; and it comprises an oil still hung from above through suitable supporting members and having a depending fire box or combustion chamber, the weight of said fire box being also carried by said supporting members and said fire box comprising arch members of metal carrying locked or supported refractory material, said still and said fire box being so constructed and arranged as to enable easy repair of said 10 still or fire box without disassemblage of the whole structure; all as more fully herein-after described and as claimed.

Oil stills as usually constructed are horizontal or vertical, cylindrical metal structures, externally fired and generally of considerable size, the capacity ranging from one hundred to fifteen hundred barrels. As ordinarily operated, they receive a charge of oil and are progressively heated, giving 20 various cuts or fractions of distillate at the various temperatures. Distillation is generally pushed far enough to leave a thick residue or even a coky mass in the still; and the end temperature may be a red heat. At the 25 end of a distillation the still is recleaned and recharged with oil for another operation. These alternations of temperature and the fact that carbon is invariably deposited on the heating surfaces, baking on as a hard 30 coky mass which requires considerable energy to remove and which is apt to cause buckling of the still plates, render it difficult to provide good and permanent settings and to repair the still. In the ordinary setting, the walls which form or inclose the fire box or combustion chamber are also the walls which support the weight of the still.

In the present invention I have rearranged the still and its setting so as to make the 35 fire box and the supporting members for the

still structurally independent. To this end, I suspend the still body from overhead members, the still serving to support the fire box. With this method of setting, expansion and contraction or buckling in the still body cannot influence the fire chamber while, on the other hand, it is possible to repair the still without destroying the walls. The fire chamber I advantageously make of a series of arch bars of cast iron or other metal, these arch members being connected at the bottom by yoke plates; and in these arch bars I key or otherwise support a lining of refractory material in such manner that they may be taken down individually 40 together with such refractory material.

In the accompanying illustration I have shown, more or less diagrammatically, a still within the present invention.

In this showing—

Figure 1 is a side elevation of the complete still and setting; Fig. 2 is a transverse vertical sectional view on line 2—2 of Fig. 1; Fig. 3 is a vertical longitudinal sectional view along line 3—3 of Fig. 2; Fig. 4 is a detail perspective view of one of the supporting arch bars; Fig. 5 is an enlarged detail sectional view of a bar, showing the pin connection; and Fig. 6 is a section through an end arch bar.

In the drawings, element 1 indicates a cylindrical still body provided with dome 2 and vapor outlets 3. This still together with its depending firebox is hung above the ground through hanger rods 4 which are 50 adjustably attached at one end to the bridge member 5 carried by upright supports or columns 5^a set in concrete base 6. At their other ends these hanger rods are attached to lugs 8 on the still body through the bolt connection shown. In addition to carrying the still body, these hangers 4 also carry the firebox which is attached directly to the still. The still is provided with a continuous angle iron lug 9 along each side. And the arch bars 10 are pinned to these as shown. There is a series of arch bars 10 on each side of the still and they together with the bottom 11 comprise the firebox which is of inverted arch-shaped form. Each of the 55 60 65 70 75 80 85 90 95

arch bars 10 is of such a shape as to enable it to carry refractory material which may be in the form of bricks, tiles or other suitable fire-resisting elements. When of brick there are advantageously several layers which are so arranged that their joints break. The arch bars 10 being of the curved form permit keying of the bricks in place with a result that any one of the bars may be independently removed from the still body. For the purpose of independently removing individual bars I advantageously arrange the refractory material of one arch bar independent of the refractory material of the other arch bar.

15 The bottom or yoke plates 11 are filled with firebrick, tile or refractory material. When the lining is of bricks the joints are preferably broken as is the case with the 20 bricks of the arch bars. The arch bars and yoke plates are bolted together through their abutting flanges. As many arch bars and yoke plates as are necessary may be used. If desired, when bricks are used as 25 the refractory material for the arches and the yoke plates they may be laid in several layers, the first or second layer consisting of bricks laid in place flat while the last layer consists of bricks securely bonded together.

30 In assembling the firebox on the still the individual arch bars are first hung in place and then their corresponding yoke plates are attached in position. The front wall 14 of the still body is composed of the firebrick or 35 refractory material and a steel plate. This front wall carries doors 15 through which oil or gas burner 16 passes. Any convenient method of heating may be used. The fire chamber is closed by wall 17 which is also of 40 refractory material. Manhole casings 18 and 19 pass through walls 14 and 17 respectively and afford access to the interior of the still. Tar line 20 is provided for emptying the still and V-shaped baffle wall 27 for 45 protecting the tar line.

Within the fire chamber are bridge wall 21, back wall 22 and arch 23. Flue 24 goes to a stack 28.

The top of the still may be jacketed by a 50 nonconductive layer 25 of tile and felt or asbestos.

With the described setting in which the still is hung from above and the firebox is hung from the still, clearing the ground, it 55 will be obvious that since the only points of support are afforded by the hanger rods from the structural steel frame work, the still is free to expand, contract, vibrate or move in any direction without cracking the 60 brickwork, which will move with the still. Buckling of the still does no harm to the furnace walls or supports. The firebox being made of a plurality of separate units, assemblage and disassemblage are ready and

easy. All that is necessary in effecting a 65 small repair to the still bottom or the firebox is to unbolt a given arch bar from the yoke plate or plates, remove the steel pin uniting it with the angle iron lug and lower the arch bar. In this operation the loss of 70 brick is slight since the bricks in the arch bar are keyed in and generally can all be removed with it.

What I claim is:—

1. In a still and still setting, a structural 75 steel framework comprising bridge members and columns, a still body, hanger rods supporting said still body from said bridge members and a fire box hung from said still body.

2. In a still and still setting, a suitably supported cylindrical still body, a plurality of arch bars of metal suspended from each side of said still, yoke plates uniting the bottom of said arch bars and completing the 85 arch and a lining of refractory material for said arch.

3. In a still and still setting, a suitably supported still body and a depending fire box for said still suspended from the sides 90 thereof, said fire box comprising a plurality of metal arch bars provided with lugs allowing a layer of arch brick to be keyed into each such bar.

4. In a still and still setting, a suitably supported cylindrical oil still having a longitudinal lug on each side, a plurality of metal arch bars pinned into each such lug and suspended therefrom, a bottom yoke plate uniting the ends of the two series of 100 arch bars thus formed and a lining of refractory material for the inverted arch formed by such arch bars and the bottom yoke plate.

5. In a still and still setting, a framework 105 having bridge members, a cylindrical oil still suspended within said framework from said bridge members and an arch-shaped fire box inclosing the bottom of said still and supported from its sides, said fire-box 110 being free to move with the still.

6. A still and still setting comprising supporting members, hangers depending from said supporting members, a still body supported by said hangers and a fire box 115 supported solely from said still body.

7. A still and still setting comprising a suitably supported still body; a fire box supported solely thereby, and means for hanging the still at such an elevation that the 120 fire box is free from the ground and the still body is free to expand, contract, vibrate or move in any direction with temperature changes.

8. In a still and still setting, a suitably 125 supported still body and a fire box hung therefrom, said fire box comprising a plurality of refractory-material supports, re-

fractory material located in each of said supports, the refractory material of one support being independent of the refractory material of another support, and means for removably attaching said supports to the still body.

9. In a still and still setting, a suitably supported still body and a fire box hung

from and supported solely thereby, said fire box comprising a plurality of refractory-¹⁶
material supports removably attached to the still body and independently detachable therefrom.

In testimony whereof, I affix my signature.

HERBERT HENDERSON.
